Application July 11, 1933, Serial No. 679,868

15 Claims. (Cl. 246—253)

Our invention relates to railway switch operating apparatus, and particularly to improvements in apparatus of the type described and claimed in Letters Patent of the United States No. 5 1,791,799, granted to J. P. Coleman, on February 10, 1931.

We will describe several forms of apparatus embodying our invention, and will then point out the novel features thereof in claims.

10 In the accompanying drawings, Fig. 1 is a longitudinal vertical sectional view showing one form of apparatus embodying our invention. Fig. 2 is a top plan view of the apparatus shown in Fig. 1, with the covers for the casing removed to better 15 illustrate the construction of the mechanism. Fig. 3 is a horizontal sectional view of the apparatus shown in Fig. 1 taken substantially on the line III—III of Fig. 1. Fig. 4 is a view similar to Fig. 1 illustrating the positions that certain of the parts 20 shown in Fig. 1 assume when the apparatus is in condition to be operated manually. Fig. 5 is an enlarged sectional view of the lock unit L shown in Fig. 2. Figs. 6 and 7 are sectional views taken on the lines VI—VI and VII—VII, respectively, of 25 Fig. 5. Fig. 8 is an enlarged top plan view of the cover 11 shown in Fig. 1. Fig. 9 is a sectional view taken on the line IX—IX of Fig. 8. Fig. 10 is an enlarged detail view of certain of the parts in the positions in which they are shown in 30 Fig. 1.

Similar reference characters refer to similar parts in each of the several views.

Referring first to Figs. 1 to 3, inclusive, the 35 switch apparatus embodying our invention is here shown as inclosed in a casing A made up of three castings 1, 2 and 3 held together by bolts 4 and 5. Secured to the underside of the casing A by means of bolts 6 and 7 extending downwardly 40 through suitable holes in the castings 1 and 2, respectively, as best seen in Fig. 1, are two plates 8 and 9 provided with holes 10 through which lag screws or other fastening devices may be passed for securing the casing to a suitable support, such as the ties of a railway track. Casting 2 is formed 45 with two compartments 2^a and 2^b, compartment 2^a being closed by a removable cover 11 and compartment 2^b being closed by a removable cover 12.

As best seen in Fig. 3, the casting 1 is formed 50 with two parallel cylinders 13^a, 13^b which are closed at their outer ends by means of cylinder heads 14^a, 14^b, and which communicate at their inner ends with the compartment 2^a of casting 2 through openings 15^a, 15^b. Pistons 16^a, 16^b are mounted for reciprocation in the cylinders 13^a, 55 13^b and are attached to the end of rack bars 17^a, 17^b which extend through the openings 15^a, 15^b into the compartment 2^b of the casting 2 for intermeshing engagement with the opposite sides of a gear wheel 18. The gear wheel 18 is keyed 60 to a vertically extending jackshaft 19, the lower

end of which is journaled in a bearing 20 formed in the casting 2 as best seen in Fig. 1, and the upper end of which is journaled in a bearing 21 formed in a plate 22 attached to the casting 2. A crank 23 is provided on the lower end of the shaft 5 19, and this crank carries a roller 24 which cooperates with a suitable slot 25 extending transversely across the top of a switch operating rod 26, as shown in Figs. 1 and 3. The rod 26 is slidably mounted in the lower part of the casting 2, 10 and is adapted to be connected at its outer ends with the movable rails of the track switch or other similar device not shown in the drawings.

Fluid pressure may be admitted to the interior of the cylinders 13^a, 13^b through ports 27^a, 27^b which are provided in the cylinder heads 14^a, 14^b, and which communicate with pipes 28^a, 28^b through valves 29^a, 29^b, as best seen in Figs. 1 and 3. When the valves occupy the positions shown in Fig. 1 communication is established between the 20 pipes 28^a, 28^b and the interiors of the cylinders, but when they are rotated from the positions shown in Fig. 1 through a sufficient angle in a counter-clockwise direction, the cylinders are disconnected from the pipes 28^a, 28^b and are 25 connected with atmosphere through vent plugs 30^a, 30^b. During the normal operation of the apparatus, the valves 29^a, 29^b occupy their open positions in which they are illustrated in Fig. 1, and fluid pressure from the source is selectively 30 admitted to the cylinders 13^a, 13^b through suitable valves (not shown) provided in the pipes 28^a, 28^b. The pistons 16^a, 16^b are so arranged in the cylinders that when one piston is at the 35 end of its stroke in one direction, the other piston will be at the end of its stroke in the other direction. It will be apparent, therefore, that if fluid pressure is admitted to cylinder 13^b when the parts are in the positions in which they are shown in Fig. 3, piston 16^b will move rack bar 17^b to 40 toward the right, thereby rotating gear wheel 18 in a clockwise direction, and hence moving rack bar 17^a and piston 16^a toward the left. Similarly, if fluid pressure is admitted to cylinder 13^a, when the parts are in the last named positions, piston 45 16^a will move rack bar 17^a toward the right, thereby rotating gear wheel 18 in a counter-clockwise direction, and hence moving rack bar 17^b and piston 16^b toward the left. It follows, that the gear wheel 18 and jackshaft 19 can be 50 given either a counter-clockwise or clockwise motion by admitting fluid pressure to the proper cylinder 13^a or 13^b. When the jackshaft 19 is rotated in a clockwise direction, the switch operating rod 26 is moved downwardly as viewed in 55 Figs. 2 and 3 by the roller 24 on crank 23, and conversely, when the shaft is rotated in the opposite direction, the switch operating rod is moved upwardly by the roller 24.

Fluid pressure may be supplied to the pipes 60

28^a and 28^b selectively for the control of the apparatus by any suitable means forming no part of our present invention and therefore not shown in the drawings.

5 The pistons 16^a, 16^b are formed with centrally disposed rearwardly extending plungers 31^a, 31^b which are adapted to enter axially disposed cylindrical bores 32^a, 32^b provided in the cylinder heads 14^a, 14^b, as the pistons approach the limits 10 of their strokes. The bores 32^a, 32^b communicate directly with the inlet passages 27^a, 27^b and it will be apparent, therefore, that as soon as the end of the plunger enters the corresponding bore, the fluid which remains in the cylinder between 15 the piston and the cylinder head is trapped in the cylinder. As a result, during the remainder of the stroke of the piston, this trapped air becomes compressed, thereby cushioning the action of the entire apparatus.

20 The right-hand ends of the rack bars 17^a, 17^b, that is to say, the ends opposite to the pistons 16^a, 16^b are provided with cylindrical guides 33^a, 33^b which are slidably mounted in cylindrical guideways 34^a, 34^b formed in the lower part of 25 the casting 2. The right-hand ends of the rack bars are also provided with locking dogs 35^a, 35^b which extend into the casting 3 through suitable openings 36^a, 36^b, and cooperate with suitable apparatus for locking the switch. This locking apparatus forms no part of our present invention, 30 and is described in detail in the previously referred to Coleman Patent No. 1,791,799.

35 The switch operating apparatus also comprises a circuit controller B for controlling signals or other traffic governing devices in accordance with the positions of the switch operated by the apparatus. This circuit controller is located in the compartment 2^b of the casting 2, and as here shown comprises three terminal boards 39, 39^a and 39^b secured to the bottom of the compartment 2^b in parallel spaced relation. Attached to the central terminal board 39 is a first set of resilient contact fingers 40^a, and a second set of resilient contact fingers 40^b. Each finger 40^a cooperates 40 at its free end with a pair of fixed contact fingers 41^a, 42^a mounted on the terminal board 39^a, while each finger 40^b cooperates at its free end with a pair of fixed contact fingers 41^b, 42^b mounted on the terminal board 39^b. The resilient contact fingers 40^a, 40^b are moved into and out of engagement with the associated fixed contact fingers by means of blocks 43^a, 43^b of insulating material which are mounted for longitudinal sliding movement between the central terminal board 39 and the outer terminal boards 39^a and 39^b, respectively. The blocks 43^a, 43^b are provided with pairs of vertically extending pins 44^a, 44^b for engagement with the opposite sides of each of the associated contact fingers 40^a and 40^b, respectively, and are moved longitudinally by means of a pair of bell crank levers 45^a, 45^b. These levers are pivotally mounted on upstanding pins 46^a, 46^b secured to the bearing plate 22, and the arms 47^a, 47^b of these levers are connected with the blocks 43^a, 43^b by means of links 48^a, 48^b. The other arms 49^a, 49^b of the levers 45^a, 45^b are provided with rollers 50^a, 50^b for engagement with a cam 51 which is fixed to the upper end of the jackshaft 19, and which is provided with a notch 52. The arms 49^a, 49^b of the levers are connected by means of a coil spring 53 so as to normally bias the arms 49^a, 49^b of these levers toward each other and the rollers 50^a, 50^b carried thereby into engagement with the cam 51.

75 The parts are so constructed and so propor-

tioned that when the piston 16^a reaches the limit of its travel toward its right-hand position shown in Fig. 3, the cam 51 has been rotated to its extreme counter-clockwise position in which the notch 52 therein registers with the roller 50^a of the bell crank lever 45^a. This permits the lever 45^a to swing in a counter-clockwise direction and causes engagement of the resilient contact fingers 40^a with their associated fixed contact fingers 41^a. During these movements of the parts, 10 the high portion of the cam 51 maintains the bell crank lever 45^b in a position in which the resilient contact fingers 40^b are in engagement with their cooperating fixed contact fingers 41^b. When the piston 16^a moves to the left, however, 15 the cam 51 is rotated in a clockwise direction. At the beginning of this movement the roller 50^a is first forced outwardly from engagement with the notch 52 which causes the bell crank lever 45^a to swing about its pivot in a clockwise 20 direction. This causes the resilient contact fingers 40^a to move out of engagement with the associated fixed contact fingers 41^a and into engagement with the associated fixed contact fingers 42^a. When the piston reaches the limit 25 of its movement to the right, the cam 51 has been rotated to a position in which the notch 52 registers with the roller 50^b of the bell crank lever 45^b. This permits the bell crank lever 45^b to swing about its pivot in a clockwise direction 30 and cause the resilient contact fingers 40^b to move out of engagement with the associated fixed contact fingers 41^b and into engagement with the associated fixed contact fingers 42^b. It will be noted that, by reason of the fact that there is but a single notch 52 in the cam 51, the levers 45^a, 45^b operate in succession and when one of these levers occupies its innermost position, the other lever is in its outermost position. As a result, certain of the contacts controlled by one of the levers 45^a, 45^b are opened and others closed, 35 at the beginning of the movement of the mechanism in either direction, but the contacts controlled by the other lever are not disturbed until the movements of the parts terminate.

40 It is occasionally desirable to operate the switch manually and independently of the fluid pressure mechanism. At such times it is desirable to disconnect the cylinders 13^a, 13^b from the pipes 28^a, 28^b to insure that the fluid pressure mechanism will not be operated during this manual operation, and result in possible injury to the operator. With apparatus embodying our invention, one form of which we will now describe, it is impossible to actuate the switch manually as 45 long as the cylinders are in communication with the pipes 28^a, 28^b, and conversely, it is impossible to operate the switch by fluid pressure while it is in condition to be operated manually.

50 This apparatus, as here shown, comprises a gear wheel 54 (see Figs. 1 and 4) which is secured to the upper face of the gear wheel 18, and which is adapted to be rotated manually by means of a pinion 55 fixed to the lower end of a shaft 56 which is provided at its upper end with a 55 crank handle 57. This pinion is adapted to be inserted into the compartment 2^a of the casting 2 through an aperture 58 provided in the cover 11, through a bearing 59 formed on the plate 22, and into intermeshing engagement with the gear wheel 54. The lower end of the pinion 55 is provided with an axially disposed gudgeon 60 for rotatable engagement with a step bearing or seat 61 formed in the housing 1, so as to maintain the pinion in intermeshing engagement with 60

gear wheel 54 of the manually operated device, which they are shown in Fig. 4, which position we will hereinafter refer to as "fluid off" positions.

During the operation of the device by fluid pressure, access to the gear 54 through the bearing 59 is prevented by means of a rod 62 which is slidably mounted in a lock device L to be described hereinafter, and which projects through diametrically disposed apertures 64 provided in the bearing 59. This rod forms an obstruction across the opening in the bearing 59 and prevents the pinion 55 from being inserted as long as the rod 62 occupies this position. The outer end of the rod 62 is pivotally connected by means of a link 65 with a T-shaped member 66 which is formed with sockets at each end for engagement with the squared confronting ends 67^a, 67^b of the valves 29^a, 29^b. The member 66 is also provided with a socket 68 adapted to receive a removable operating lever, such as the crank handle 57.

When the valves 29^a, 29^b occupy the positions shown in Fig. 1, in which communication is established between the pressure supply pipes 28^a, 28^b and the interior of the cylinders 13^a, 13^b, the rod 62 completely obstructs the opening in the bearing 59, thereby rendering it impossible for the pinion 55 to be inserted in order to operate the switch manually. However, if it is desired to operate the switch by means of the pinion 55, a lever is inserted in the socket 68 and the member 66 and the valves 29^a, 29^b are turned to the positions shown in Fig. 4, in which positions communication between the fluid pressure supply and the interiors of the cylinders 13^a, 13^b is interrupted, and in which communication is established between the cylinders and the outer atmosphere through the vent plugs 30^a, 30^b. When the member 66 is thus operated, the rod 62 is withdrawn longitudinally through the apertures 64 in the bearing 59 to the retracted position illustrated in Fig. 4, in which it no longer prevents access through the opening in this bearing. This permits the pinion 55 to be inserted through the bearing 59 in order to manually operate the gear 54 and the parts connected therewith.

Referring now also to Figs. 5, 6 and 7, the previously referred to lock unit L comprises a casing 70 made up of two separate castings 70^a and 70^b secured together by means of screws 71. The casting 70^a is formed with a tubular portion 72 which projects through a hole 73 in the side of the casting 2, and which is exteriorly screw-threaded at its inner end for the reception of a suitable nut 74 by means of which the entire lock unit is secured to the casting 2. The hole 72^a in the tubular portion 72 of the casting 70^a aligns with a hole 75 in the casting 70^b, and these aligned holes slidably receive the previously described rod 62. A cylinder lock 76 is secured by means of screws 77 within a boss 78 formed in the outer side of the casting 70^b, and the inner end of the barrel of this lock carries a cam 79 which cooperates with a lateral projection 80 formed on the side of a locking dog 81. The locking dog is pivoted at one end on a stud 82 secured to the casting 70^a, and cooperates at its free end with a notch 83 formed in the upper side of the rod 62. A spring 84 is interposed between the upper side of the casting 70^b and the locking dog 81, and constantly biases the locking dog to the proper position to enter the notch 83. The notch 83 is so disposed in the rod 62, and the parts are so proportioned that this notch will align with the locking dog when and only when the valves 29^a and 29^b occupy the positions in

which they are shown in Fig. 4, which position we will hereinafter refer to as "fluid off" positions. With the lock unit L constructed in the manner just described, when the lock barrel occupies the position in which it is shown in the drawings, which position is its normal position, the cam 79 is out of engagement with the projection 80 on the locking dog 81, and under these conditions, if the valves 29^a and 29^b are moved toward their "fluid off" positions, the spring 84 assisted by gravity, will rotate the locking dog to the position in which it enters the notch 83 in the rod 62 slightly before the end of rod 62 clears the bearing 59 in plate 22, thus locking the valves in their "fluid off" positions. After the valves have once been locked in their "fluid off" positions in this manner, it is necessary, before they can be subsequently restored to their "fluid on" positions to insert the key in the lock 76, and rotate the lock barrel through an angle of approximately 180° in a clockwise direction, as viewed in Fig. 5. This rotation of the lock barrel, of course, rotates the cam 79 through a corresponding angle, thereby causing the high portion 79^a of the cam 79 to move into engagement with the projection 80 on the locking dog 81, which raises the locking dog to an upper position in which its lower edge is clear of the notch 83. The rod 62 is then free to move, and the valves 29^a and 29^b can then be restored to their "fluid on" positions in the manner previously described. The key for the lock 76 cannot be removed from the lock, however, until the lock barrel has been restored to its normal position.

The reference character 85 designates a gravity latch which is provided for the purpose of preventing accidental movement of the valves 29^a and 29^b away from their "fluid on" positions. This latch is pivotally attached at one end to the link 65, and is provided at the other end with a latch surface 85^a which, when the parts are in their "fluid on" positions, and the latch is in its normal position as shown in Fig. 1, engages the head of a bolt 86 comprising one of the bolts which fastens the cylinder head 14^a to the casting 1. It is obvious that when the latch surface 85^a is engaging the bolt 86, accidental movement of the link 65 toward the left, and hence of the valves 29^a and 29^b away from their "fluid on" positions is prevented. The latch 85 is biased to its normal position by gravity. Formed in the latch 85 intermediate its ends is a transverse hole 85^b which aligns with a similar hole 87 in the link 65 when the latch occupies its normal position. The two holes 85^a and 87 are adapted to receive a suitable locking device such as a cotter pin, and it will be apparent that when a cotter pin is passed through these holes, the latch and associated parts will be secured in the positions shown in Fig. 1. Provided on the left-hand end of the latch 85 directly above the latch surface 85^a is a projecting finger grip lug 85^c by means of which the latch may be raised to a position in which the latch surface 85^a is clear of the bolt 86; and provided on the right-hand end of the latch above its pivotal axis is a laterally projecting lug 85^d which is adapted to cooperate with the upper surface of the link 65 to limit the upward travel of the latch. The right-hand end of the latch is also provided with a depending lug 85^e which cooperates with the head of the bolt 86 to prevent the valves 29^a and 29^b from being moved past their "fluid off" positions. The latch is further provided with a horizontal rib 85^f which, when the latch has been raised far enough to permit

the latch surface 85^a to clear the head of the bolt 86 and the link 65 has been moved toward the left far enough to move the latch surface 85^a past the head of the bolt, rides on the edge of the cylinder head 14^b in such manner that the latch is held in its raised position. The manner in which the latch cooperates with the apparatus as a whole will be obvious from the foregoing description and from an inspection of the drawings 10 without further detailed description.

For reasons which are obvious, it is desirable that the aperture 58 in the cover 11 should be tightly closed at all times except when pinion 55 is in place for manual operation of the switch, 15 and for the purpose of accomplishing this desirable result, we provide an auxiliary cover 88 which is constantly biased to a closed position in a manner which we will now describe. As best seen in Figs. 1, 8 and 9, the auxiliary cover 20 88 is secured to one horizontal leg 89^a of a U-shaped bracket 89, the other leg 89^b of which is secured to one end of an arm 90 which is loosely pivoted at its opposite end on a stud bolt 91 secured to the underside of the cover 11. Formed 25 on the right-hand side of the arm 90 as viewed in Fig. 8 is a laterally projecting lug 92, and stretched between this lug and a stud 93 secured to the cover 11 is a coil spring 94 which biases the arm 90, together with the U-shaped bracket 30 89 and auxiliary cover 88, to the proper angular position relative to the cover 11 to close the aperture 58, the parts being stopped in their proper positions by engagement of the closed side of the U-shaped bracket with the side of the aperture. The stud bolt 91 about which the arm 90 35 pivots is considerably longer than the thickness of the arm, and disposed on this bolt between the head of the bolt and the underside of the arm is a compressed coil spring 95 which constantly exerts an upward force on the right-hand end of the arm. This upward force is converted into a downward force at the left-hand end of the arm, by means of a depending rib 96 (see Fig. 1) on the cover 11, about which the arm is adapted to pivot intermediate its ends. 40

It will be seen, therefore, that the auxiliary cover is constantly biased to the proper horizontal position to close the aperture 58. A finger grip lug 97 is provided on the left-hand side of the auxiliary cover, as viewed in Fig. 8, and when 45 it is desired to insert the pinion 55 through the aperture 58, the auxiliary cover is grasped by means of this finger lug and raised slightly, after which it is rotated about the stud bolt 91 as a center through an angle of approximately 35° or 40° in the direction of the arrow shown in the cover. The pinion 55 is then inserted through 50 the aperture 58 and the cover is released. When this is done, the spring 94 will rotate the cover 55 88 in the direction opposite to that indicated by the arrow until its lower side as viewed in Fig. 8 rests against the side of the pinion shaft. The parts are so proportioned that when the cover is in this latter position, it will not interfere with the hand operation of the apparatus. Upon removal of the pinion 55 from the aperture 58, the springs 84 and 95 operate in turn 60 to swing the cover to its closed position in which it is shown in the drawings.

70 A further feature of our invention consists in novel means for operating the circuit controller B simultaneously with the movement of the valves 29^a and 29^b to their "fluid on" positions to provide an indication that the movement is being rendered ineffective for power operation. As here

shown, this means comprises a motion plate 98 which is slidably mounted on a step bearing 99 formed on the upper side of the cam 51, and which is guided by a rod 100. One end of the rod 100 is secured to the right-hand side of the motion plate, and the other end of this rod projects into a guideway 101 formed in an upstanding projection 102 provided on the bearing plate 22. The motion plate 98 is adapted to be moved between a right-hand extreme position in which it is shown in Fig. 1 and a left-hand extreme position in which it is shown in Fig. 4, and is provided at its opposite sides with two laterally projecting cams 103^a and 103^b which cooperate with the rollers 50^a and 50^b, respectively, on the 15 arms 49^a and 49^b of the levers 45^a and 45^b in such manner that as soon as the motion plate is moved away from the right-hand extreme position shown in Fig. 2, the roller 50 which then occupies the notch 52 in the cam 51 will be forced 20 out of this notch, thus operating the contacts controlled by the associated rocker arm in the same manner as when the roller is forced out of the notch 52 during power operation of the apparatus. For example, as shown in the drawings, the roller 50^a on the arm 49^a of the lever 45^a is in the notch 52 in the motion plate 51, so that the contacts 46^a—41^a of circuit controller B are closed and the contacts 40^a—42^a are open. If, now, the motion plate 98 is moved toward the 30 left from the extreme position shown to its other extreme position the cam 103^a will engage the roller 50^a and will force it out of the notch 52. This movement of the roller out of the notch 52 will act through the lever 45^a, connecting rod 35 48^a and block 43^a to move the contact fingers 40^a from the positions in which they engage the fixed contact fingers 41^a to the positions in which they engage the fixed contact fingers 42^a, thereby opening the contacts 40^a—41^a and closing the 40 contacts 40^a—42^a. A spring 104 surrounds the rod 100 between the projection 102 on the bearing plate 22 and the right-hand side of the motion plate 98, and constantly biases the motion plate toward its extreme left-hand position. 45

A latch piece 105 (see Fig. 10) is pivotally attached at one end to the left-hand side of the motion plate 98, and this latch piece is provided with an integral upstanding rib 106 which cooperates with the end of the rod 62 to at times hold the motion plate in the extreme position shown in opposition to the bias of the spring 104 as will be more fully described presently. The latch piece 105 is also provided with two rollers 107 and 108, the one of which 108 is disposed above and a little to the left of the other roller 107. The roller 107 cooperates with a cam 109 formed on the bearing plate 22, while the roller 108 cooperates with a notch 110 provided in the underside of the rod 62. 60

The parts are so proportioned that when the valves 29^a and 29^b are in their "fluid on" positions, the rod 62 will engage the rib 106 on the latch piece 105 and will hold the motion plate in the positions shown. When the motion plate occupies this position, the cams 103^a and 103^b are so positioned with respect to the associated rollers 50^a and 50^b that these cams will not interfere with the normal operation of the circuit controller. Furthermore, when the motion plate occupies the 70 position shown, the roller 107 is in engagement with the cam 109 and holds the latch piece 105 in a position in which the roller 108 enters the notch 110 in the rod 62, so that the latch piece is then operatively connected with the rod 62. 75

We will now assume that the member 66 is operated to move the valves 29^a and 29^b from their "fluid on" positions to their "fluid off" positions. This movement of the member 66 moves the rod 62 toward the left in the manner previously described, and since roller 108 is now held within the notch 110 in the rod 62 by engagement of roller 107 with cam 109, it will be apparent that this movement of the rod 62 toward the left will move the motion plate 98 along with the rod, until the motion plate has been moved to the position in which the roller 107 moves out of engagement with the cam 109. When this happens, the roller 108 moves out of the notch 110 in the rod 62, thereby disconnecting the rod 62 from the motion plate. The parts are so proportioned that when the rod becomes disconnected from the motion plate, the motion plate will have been moved to the extreme position in which it is shown in Fig. 4, and as was previously pointed out, when the motion plate occupies this position, the roller 50 which previously occupied the notch 52 in the motion plate 51 is forced out of this notch, thereby operating the contacts of circuit controller B to a position to indicate that the apparatus has been rendered ineffective for power operation. After the motion plate has been moved to the extreme position shown in Fig. 4, the spring 104 operates to maintain it in this position. The rod 62 now being disconnected from the motion plate may be withdrawn from the bearing 59 in the manner previously described to permit the pinion 55 to be inserted in place for hand operation.

When the valves 29^a, 29^b are subsequently restored to their "fluid on" position, the rod 62 is again projected across the opening in the bearing 58, and into engagement with the upstanding rib 106 on the latch piece 105. The engagement of the rod 62 with the rib 106 causes the latch piece and motion plate 98 to move toward the right, and as the latch piece moves toward the right, the roller 107 rides up onto the cam 109 which restores the latch piece to the positions shown in Fig. 1, thus causing the roller 108 to reenter the notch 110 in the rod 62. The movement of the motion plate 98 toward the right moves the cams 103^a and 103^b out of engagement with the associated rollers 50^a and 50^b on the levers 47^a and 47^b, and thus permits the roller 50 which is then in alignment with the notch 52 in the cam 51 to re-enter this notch, thereby restoring the contacts of circuit controller B to their proper positions for power operation of the switch.

It should be pointed out that when the motion plate 98 and latch piece 105 are in the positions which they occupy when the apparatus is in condition for hand operation as shown in Fig. 4, the latch piece is in such close proximity to the adjacent side of the bearing 59 that any upward movement of the latch piece 105, due to vibration, is prevented.

Although we have herein shown and described only one form of railway switch operating apparatus embodying our invention, it is understood that various changes and modifications may be made therein within the scope of the appended claims without departing from the spirit and scope of our invention.

Having thus described our invention, what we claim is:

1. Railway switch operating apparatus comprising a casing, a switch actuating shaft journaled in said casing, fluid pressure operated means for actuating said shaft between two ex-

treme positions, valve mechanism for controlling the admission of fluid to said fluid pressure operated means, said valve mechanism having a first position in which the admission of fluid to said fluid pressure operated means is permitted and a second position in which the admission of fluid to said fluid pressure operated means is prevented, a cam secured to said switch actuating shaft, a motion plate movable between a first and a second position, means for moving said motion plate to its first position or its second position according as said valve mechanism is moved to its first or its second position, and a circuit controller controlled by said cam and said motion plate.

2. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a cam secured to said switch actuating shaft, a motion plate movable between a first and a second position, means for moving said motion plate to its first position or its second position according as said valve mechanism is moved to its first or its second position, and a contact controlled jointly by said motion plate and said cam and so arranged that said contact will be closed when and only when said shaft occupies one extreme position and said motion plate occupies its first position.

3. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a cam secured to said switch actuating shaft, a motion plate movable between a first and a second position, means for moving said motion plate to its first position or its second position according as said valve mechanism is moved to its first or its second position, a first contact controlled jointly by said motion plate and said cam and so arranged that said contact will be closed when and only when said shaft occupies one extreme position and said motion plate occupies its first position.

4. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a cam secured to said switch actuating shaft, a motion plate movable between a first and a second position, means

for moving said motion plate to its first position or its second position according as said valve mechanism is moved to its first or its second position, a first contact controlled by said motion plate and said cam in such manner that said first contact will be closed when and only when said shaft occupies one extreme position and said motion plate occupies its first extreme position, and a second contact controlled by said motion plate and said cam in such manner that said second contact will be closed when said shaft occupies any position but said one extreme position or when said motion plate occupies any position but its first position.

5 5. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a cam secured to said switch actuating shaft, a motion plate movable between a first and a second position, means for moving said motion plate to its first position or its second position according as said valve mechanism is moved to its first or its second position, a first contact controlled by said motion plate and said cam in such manner that said first contact will be closed when and only when said shaft occupies one extreme position and said motion plate occupies its first position, a second contact controlled by said motion plate and said cam in such manner that said second contact will be closed when and only when said shaft occupies its other extreme position and said motion plate occupies its first position, a third contact controlled by said cam and said motion plate in such manner that said third contact will become closed whenever said shaft occupies any position but its one extreme position or whenever said motion plate occupies any position but its first position, and a fourth contact controlled by said cam and said motion plate in such manner that said fourth contact will become closed whenever said shaft occupies any position but its other extreme position or whenever said motion plate occupies any position but its first position.

10 6. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a cam secured to said switch actuating shaft, a motion plate movable between a first and a second position, a bearing in said casing adapted to receive a removable shaft for manually operating said switch actuating shaft, a rod movable between a first position in which it prevents said manually operable shaft from being inserted into said bearing and a second position in which it permits said manually operable shaft to be inserted into said bearing, means for connecting said rod with said valve mechanism in such manner that said rod will occupy its first position or its second

position according as said valve mechanism occupies its first position or its second position, means controlled by said rod for moving said motion plate to its first position or its second position according as said rod is moved to its first position or its second position, and a circuit controller controlled by said cam and said motion plate. 5

7. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a cam secured to said switch actuating shaft, a motion plate movable between a first and a second position, a bearing in said casing adapted to receive a removable shaft for manually operating said switch actuating shaft, a rod movable between a first position in which it prevents said manually operable shaft from being inserted into said bearing and a second position in which it permits said manually operable shaft to be inserted into said bearing, means for connecting said rod with said valve mechanism in such manner that said rod will occupy its first position or its second position according as said valve mechanism occupies its first position or its second position, means controlled by said rod for moving said motion plate to its first position or its second position according as said rod is moved to its first position or its second position, and a contact controlled jointly by said motion plate and said cam and so arranged that said contact will be closed when and only when said shaft occupies one extreme position and said motion plate occupies its first extreme position. 10 20 25 30 35 40 45 50 55 60 65 70 75 80 85 90 95

8. Railway switch operating apparatus comprising a casing, a switch actuating shaft journaled in said casing, fluid pressure operated means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a bearing in said casing adapted to receive a removable shaft for manually operating said switch actuating shaft, a rod movable between a first position in which it prevents said manually operable shaft from being inserted into said bearing and a second position in which it permits said manually operable shaft to be inserted into said bearing, means for connecting said rod with said valve mechanism in such manner that said rod will occupy its first position or its second position according as said valve mechanism occupies its first position or its second position, a cam secured to said switch actuating shaft, a motion plate movable between a first position and a second position, means controlled by said rod for moving said motion plate to its first position or its second position according as said rod is moved to its first position or its second position, a first contact controlled by said motion plate and said cam in such manner that said first contact will be closed when and only when said shaft occupies one extreme position and said motion plate occupies 55 60 65 70 75 80 85 90 95 99

- its first extreme position, and a second contact controlled by said motion plate and said cam in such manner that said second contact will be closed when said shaft occupies any position but 5 said one extreme position or when said motion plate occupies any position but its first position.
9. Railway switch operating apparatus comprising a casing, a switch actuating shaft journaled in said casing, fluid pressure operated 10 means for actuating said shaft between two extreme positions, valve mechanism for controlling the admission of fluid to said fluid pressure operated means, said valve mechanism having a first position in which fluid can be admitted to said 15 fluid pressure operated means and a second position in which fluid cannot be admitted to said fluid pressure operated means, a bearing in said casing adapted to receive a removable shaft for manually operating said switch actuating shaft.
- 20 a rod movable between a first position in which it prevents said manually operable shaft from being inserted into said bearing and a second position in which it permits said manually operable shaft to be inserted into said bearing, means 25 for connecting said rod with said valve mechanism in such manner that said rod will occupy its first position or its second position according as said valve mechanism occupies its first position or its second position, a cam secured to said 30 switch actuating shaft, a motion plate movable between a first position and a second position, means controlled by said rod for moving said motion plate to its first position or its second position according as said rod is moved to its 35 first position or its second position, a first contact controlled by said motion plate and said cam in such manner that said first contact will be closed when and only when said shaft occupies one extreme position and said motion plate occupies its first position, a second contact controlled by said motion plate and said cam in such manner that said second contact will be closed when and only when said shaft occupies its 40 other extreme position and said motion plate occupies its first position, a third contact controlled by said cam and said motion plate in such manner that said third contact will become closed whenever said shaft occupies any position but its one extreme position or whenever said motion plate occupies any position but its first position, and a fourth contact controlled by said cam and said motion plate in such manner that said fourth contact will become closed whenever said shaft occupies any position but its other extreme position or whenever said motion plate occupies any 45 position but its first position.
10. Railway switch operating apparatus comprising a casing, a switch actuating shaft journaled in said casing, fluid pressure operated 50 means for actuating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a third bearing formed in said bearing plate, said third bearing being adapted to receive a removable shaft for manually operating 55 said switch actuating shaft, a rod having a first position in which it prevents said removable shaft from being inserted into said third bearing and a second position in which it permits said removable shaft to be inserted into said third bearing, said rod being provided with a notch, a first cam secured to said switch actuating shaft, a step bearing formed on said first cam, a motion plate slidably mounted on said 60 step bearing for longitudinal movement between a first position and a second position, means for biasing said motion plate to its second position, a second cam formed on said bearing plate, a latch piece pivotally attached to said 65 70 75
- nism in such manner that said rod will occupy its first position or its second position according as said valve mechanism occupies its first position or its second position, a first cam secured to said switch actuating shaft and provided with a notch, a motion plate slidably mounted on a step bearing formed on said cam, means controlled by said rod for moving said motion plate to a first position or a second position according as said rod is moved to its first position or its second position, and a circuit controller controlled by said cam and said motion plate.
11. Railway switch operating apparatus comprising a casing, a switch actuating shaft journaled in said casing, fluid pressure means for 10 actuating said shaft from one extreme position to another extreme position, a valve for controlling the admission of fluid to said fluid pressure means, a gear wheel secured to said shaft, a bearing adapted to maintain a manually 15 operable removable pinion in operative position with respect to said gear, a rod operatively connected with said valve and extending through said bearing for obstructing access to said bearing when said valve is open and for permitting 20 said pinion to be mounted in said bearing for the manual operation of said gear when said valve is closed, a first cam secured to said shaft and provided with a notch, a roller biased into engagement with said first cam and adapted to 25 enter said notch when and only when said shaft occupies said one extreme position, a circuit controller controlled by said roller, a motion plate movable between a first and a second position, a 30 cam on said motion plate cooperating with said roller and effective when said motion plate is moved to its first position for forcing said roller out of the notch in said first cam if said roller then occupies the notch in said first cam, and means controlled by said rod for moving said 35 motion plate to its second position or to its first position according as said rod occupies the position in which it obstructs said bearing or its other position.
12. Railway switch operating apparatus comprising a casing, a first bearing formed in the bottom of said casing, a bearing plate secured to said casing and provided with a second bearing which aligns with said first bearing, a switch actuating shaft journaled in said two bearings, 50 fluid pressure actuated means for rotating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a third bearing formed in said bearing plate, said third bearing being adapted to receive a removable shaft for manually operating 55 said switch actuating shaft, a rod having a first position in which it prevents said removable shaft from being inserted into said third bearing and a second position in which it permits said removable shaft to be inserted into said third bearing, said rod being provided with a notch, a first cam secured to said switch actuating shaft, a step bearing formed on said first cam, a motion plate slidably mounted on said 60 step bearing for longitudinal movement between a first position and a second position, means for biasing said motion plate to its second position, a second cam formed on said bearing plate, a latch piece pivotally attached to said 65 70 75

motion plate, a roller secured to said latch piece and adapted to engage said second cam when said motion plate occupies its first position but not when said motion plate occupies its second position, a second roller secured to said latch piece in such manner that it will enter the notch in said rod when said first roller engages said second cam, an upstanding rib on said latch piece adapted to cooperate with the end of said rod to move said motion plate from its second position to its first position in response to movement of said rod from its second position to its first position, means for operatively connecting said rod with said valve mechanism in such manner that said rod will be moved to its first position or its second position according as said valve mechanism occupies its first position or its second position, and a circuit controller controlled by said first cam and by said motion plate.

13. Railway switch operating apparatus comprising a casing, a first bearing formed in the bottom of said casing, a bearing plate secured to said casing and provided with a second bearing which aligns with said first bearing, a switch actuating shaft journaled in said two bearings, fluid pressure actuated means for rotating said shaft between two extreme positions, valve mechanism for controlling the admission of fluid to said fluid pressure operated means, said valve mechanism having a first position in which fluid can be admitted to said fluid pressure operated means and a second position in which fluid cannot be admitted to said fluid pressure operated means, a third bearing formed in said bearing plate, said third bearing being adapted to receive a removable shaft for manually operating said switch actuating shaft, a rod having a first position in which it prevents said removable shaft from being inserted into said third bearing and a second position in which it permits said removable shaft to be inserted into said third bearing, said rod being provided with a notch, a first cam secured to said switch actuating shaft, said first cam being provided with a notch, two pivoted bell crank levers, two rollers one secured to each lever in such manner that the one roller will align with the notch in said first cam when and only when said switch actuating shaft occupies one extreme position and that the other roller will align with the notch in said first cam when and only when said switch actuating shaft occupies the other extreme position, means for biasing said two bell crank levers to positions in which the associated roller will enter the notch in said cam whenever such notch aligns with such roller, a step bearing formed on said first cam, a motion plate slidably mounted on said step bearing for longitudinal movement between a first position and a second position, means for biasing said motion plate to its second position, a second cam formed on said bearing plate, a latch piece pivotally attached to said motion plate, a roller secured to said latch piece and adapted to engage said second cam when said motion plate occupies its first position but not when said motion plate occupies its second position, a second roller secured to said latch piece in such manner that it enters the notch in said rod when said first roller engages said second cam, an upstanding rib on said latch piece adapted to cooperate with the end of said rod to move said motion plate from its second position to its first position in response to movement of said rod from its second position to its first position, means for operatively connecting said rod with said valve mechanism in such manner that said rod will be moved to its first position or its second position according as said valve mechanism occupies its first position or its second position, and a circuit controller controlled by said first cam and by said motion plate.

14. In combination, a rod movable between two extreme positions and provided with a notch, a motion plate movable between two extreme positions, a cam, a latch piece pivotally attached to said motion plate and provided with a first roller which is adapted to engage said cam when said motion plate occupies one extreme position but not when said motion plate occupies the other extreme position, a second roller secured to said latch piece in such manner that it will enter the notch in said rod when said rod occupies one extreme position and said first roller is engaging said cam, whereby said motion plate may be moved from its one extreme position to its other extreme position in response to movement of said rod from its one extreme position toward its other extreme position, an upstanding rib on said latch piece adapted to cooperate with the end of said rod to move said motion plate from its other extreme position to its one extreme position in response to movement of said rod to its one extreme position, and a circuit controller controlled by said motion plate.

15. Railway switch operating apparatus comprising a casing, a switch actuating shaft journaled in said casing, fluid pressure actuated means for operating said shaft, a valve having an open and a closed position and arranged to control the admission of fluid pressure to said fluid pressure actuated means, a bearing in said casing adapted to receive removable means for manually operating said shaft, a rod having a first position in which access to said bearing is prevented and a second position in which access to said bearing is permitted, a link pivotally attached at one end to the free end of said rod, a member attached to said valve in such manner that rotation of said member operates said valve, said member being pivotally attached to the free end of said link in such manner that said rod will be moved to its first position or its second position according as said valve is open or closed, and a latch pivotally attached to said link and biased by gravity to one position and provided with a latch engaging surface which when said latch occupies said one position engages a part of said fluid pressure means and prevents accidental movement of said valve away from its open position.

16. In combination, a rod movable between two extreme positions and provided with a notch, a motion plate movable between two extreme positions, a cam, a latch piece pivotally attached to said motion plate and provided with a first roller which is adapted to engage said cam when said motion plate occupies one extreme position but not when said motion plate occupies the other extreme position, a second roller secured to said latch piece in such manner that it will enter the notch in said rod when said rod occupies one extreme position and said first roller is engaging said cam, whereby said motion plate may be moved from its one extreme position to its other extreme position in response to movement of said rod from its one extreme position toward its other extreme position, an upstanding rib on said latch piece adapted to cooperate with the end of said rod to move said motion plate from its other extreme position to its one extreme position in response to movement of said rod to its one extreme position, and a circuit controller controlled by said motion plate.
